UNITED STATES PATENT OFFICE

ERNST WILHELM OTTO UTTER, OF HELSINKI, SUOMI-FINLAND

AEROPLANE BOMB FUSE

Application filed January 31, 1929, Serial No. 336,468, and in Suomi-Finland February 21, 1928.

It is known that the exploding mechanisms for aeroplane bombs have been more or less defective. The safety device of the bomb has especially been unsatisfactory and the 5 fuse of the bomb has often been faulty so that in cases where the axial rotation of the falling bomb has for some reason stopped this has effected a relocking of the exploding mechanism thus resulting in the failure of 10 the bomb to explode when striking an obstacle. The exploding mechanism according to the present invention is freed from these defects.

The invention provides a construction of 15 the moving elements of the safety device in the nose body of the bomb arranged in such a way that the bomb is positively secured for transportation but when the safety device once is released it can not be automatically 20 or unintentionally locked again.

The accompanying drawings illustrate one way of carrying out the invention into practice.

Fig. 1 shows the nose body of the bomb 25 with fuse and auxiliary devices in longitudinal section.

Figs. 2 and 3 are detail views illustrating 30 respectively a threaded plug with a moving pin for attachment to the nose, and a hammer with safety screw.

1 is the nose body of the bomb which is furnished with two securing plungers 2 of any usual and well known construction, the plungers acting in the conventional way when 35 the bomb is dropped and rotates around its longitudinal axis. The hammer 3 is thicker at the active end and is furnished with a hole 4, into the known way in which hole the ends of the securing plungers fit. The 40 other end 5 of the hammer 3 is cylindrical also but smaller in diameter than the active end and guides the hammer spring 6, said last named end of the hammer being provided with a threaded hole 7. Between the 45 end and point of the nose there is clearance

for the hammer to move. The thicker end of the hammer is surrounded by a sleeve or tube 8 constituting a detonator retainer and is furnished with holes corresponding to the plunger hole in the hammer, the securing 50 plungers passing through the holes of the tube 8 and extending to a predetermined extent into the hole in the hammer. The inner end of the detonator retainer 8 extends somewhat beyond the point of the hammer when 55 the detonator and the hammer are secured against operation.

The detonator 9 is made in the shape of a shot gun cartridge with a percussion cap 10 in the heel 9a, and includes a ferrule 11 with 60 a hole for the fuse 12, which is pressed against the ferrule 11 by means of a lock nut 13. The detonator is filled with the initial exploder 14 composed of tetryl or some other suitable explosive, and is loose in the tube 15, 65 which is threaded in the nose body at 16. 17 is a plate tube open at the end against the nose body and provided at said end with a flange 17a. When the bomb is filled with explosive the plate tube 17 is first inserted 70 and the bottom disc 18 with two spanner holes 18a is screwed on to such an extent as not to prevent the nose body 1 from being turned home afterwards. In the centre of the disc 18 there is a hole big enough to permit passage therethrough of the tube 15. The tube 17 thus constitutes a suitable nest in the explosive for the accommodation of the tube 15. The helical spring 19 presses the detonator against the tube 15. The use of the aeroplane bomb may be either for instantaneous 75 action of the fuse or with time lag action of the fuse.

Instantaneous action of the fuse

The tip of the nose is furnished with a centrally drilled plug 20 having a pin 21, which has a limited axial motion. One end of the pin is loosely fitted in the hole 22 of the nose 85 extending up to the hammer heel when the 90

plug 20 is turned home, and at the other end is provided with a knob 23. Through the hole 24 passes a metal wire so that the knob 23 must receive an impact powerful enough 5 to cut the wire before the pin can reach the hammer. When the bomb is dropped the twisted shape of the bomb wings will set the bomb into rotation thus releasing the securing plungers 2 by their centrifugal force and 10 releasing the hammer. When the plungers have moved far enough the detonator retainer 8 drops into the empty space 25 thus preventing the plungers entering the hole 4 and relocking the hammer 3. The spring 19 15 presses the detonator against the heel 9a and thereby prevents the detonator from dropping down on the point of the hammer. When the bomb strikes a hard obstacle, as for instance a pavement, the thrust is instantaneously transmitted from the pin 21 to the hammer thus effecting the explosion.

The fuse has time lag

The pin 21 is detached from the plug 20 by 25 removing the wire 24 and unscrewing knob which has a threaded end 23a fitting the thread in the plug 20. When the bomb is dropped the hammer is released in the manner described above. In case the bomb now 30 strikes a soft obstacle, as for instance the roof of a building, the hammer will continue to move down in the empty space 22 thus compressing the spring 6, and the detonator 9 will also drop and compress the spring 19. 35 When the bomb has stopped, the springs 6 and 19 will kick the hammer and the detonator back and when the motion of the detonator is completed the point of the hammer will strike the percussion cap 19a thus effecting 40 the explosion. These additional motions of the fuse mechanism require some time in their completion so that the bomb has penetrated deeper into the obstacle before the explosion takes place.

45 When stored or transported the detonator 9 is removed from the bomb and the pieces 20, 21 and 23 are kept in the tube 15 and a screw 26 is inserted through the hole 22, the end of the screw being threaded to correspond to the thread 7 in the hammer. By 50 means of said screw 26 it is possible to pull the hammer slightly downward so as to keep the plungers 2 positively in place by friction thus making an accidental release of the hammer impossible.

Patent claims:

1. Exploding mechanism for aircraft bombs comprising an axially movable hammer provided with a threaded recess in 60 its outer end, a detonating charge, a percussion cap therefor, means for locking said hammer against operation and adapted to be operated by centrifugal force developed in the descent of the bomb to release said 65 hammer, and a screwthreaded pin arranged

to be screwed into the threaded recess of said hammer for forcing it into engagement with said locking means to lock the latter against operation.

2. Exploding mechanism for aircraft bombs comprising a nose body provided with an axial bore, a percussion cap in registry with said bore, a hammer consisting of an active head and a stem of relatively reduced diameter movably mounted in said bore, a 70 helical spring surrounding the stem of said hammer adapted to be compressed by its inertia upon impact of the bomb with a target and to be expanded subsequently as said bomb is retarded by said impact to force 75 said hammer against said percussion cap to effect a retarded explosion, and a firing pin adapted to be removably connected with said nose body and projecting beyond the end thereof for forcing said hammer against said 80 percussion cap to effect an instantaneous explosion upon impact with a target.

3. Exploding mechanism for air craft bombs as set forth in claim 2 in which the hammer is provided with a transverse hole 90 into which radially movable pins normally project to lock said hammer in its inoperative position, said pins being operated by centrifugal force developed by rotation of the bomb in the descent thereof to release said hammer, and a sleeve loosely mounted on said hammer and adapted, upon the movement of said pins to releasing positions, to drop between said pins and the hammer to prevent relocking of the latter in case rotation 95 of the bomb ceases during its descent.

4. Explosion mechanism for air craft bombs as set forth in claim 2 in which a detonator charge is axially movable in a detonator tube projecting from said nose 105 body, and retained in said tube by means of a spring having its one end bearing against said nose body.

5. Explosion mechanism for air craft bombs comprising a nose body provided with 110 an axial bore, a detonator tube mounted on said body in registry with said bore, a detonator charge movably mounted in said detonator tube, a hammer movably mounted in said bore for exploding said detonator charge, 115 means for releasably locking said hammer in its inoperative position, and a sleeve for preventing relocking of said hammer subsequently to its release and for preventing said detonator charge from striking against said 120 hammer when the latter is locked in its inoperative position.

6. The combination of an aircraft bomb, the nose of which is provided with a threaded recess, and exploding mechanism comprising 125 an axially movable hammer, a detonating charge, a percussion cap, a firing pin removably mounted in the bomb and provided with a corresponding threaded recess, said 130 firing pin projecting outwardly beyond the

end of said bomb and adapted to transmit the initial impact of said bomb against the target to said hammer whereby the latter is driven against said percussion cap to explode 5 the detonating charge coincidentally with said impact, and a solid knob arranged to be interchangeably threaded into either of said recesses.

In witness whereof I have hereunto set my
10 hand.
